Primary Examiner — Ricky Pham(74) *Attorney, Agent, or Firm* — Schwabe, Williamson & Wyatt, P.C.(57) **CLAIM**

We claim an ornamental design for a spoon, as shown and described.

DESCRIPTION

FIG. 1 is a perspective view of a spoon, showing our new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The dashed lines are included for illustrating interior and/or environmental structures and form no part of the claimed design.
